UNITED STATES PATENT OFFICE

171,471

SHOE HEEL

William J. Walsh, Lemay, Mo.

Application November 17, 1952, Serial No. 22,319

Term of patent 14 years

(Cl. D7—5)

To all whom it may concern:

Be it known that the undersigned, William J. Walsh, a citizen of the United States, residing at Lemay, St. Louis County, State of Missouri, has invented a new, original, and ornamental Design for a Shoe Heel, of which the following is a specification, reference being had to the accompanying drawing, forming a part thereof, in which:

Fig. 1 is a top view of a shoe heel showing my new design;

Fig. 2 is a side elevation thereof;

Fig. 3 is a rear view thereof.

The dominant features are shown in full lines.

I claim:

The ornamental design for a shoe heel, substantially as shown and described.

WILLIAM J. WALSH.
